UNITED STATES PATENT OFFICE.

ANDREW E. MACCOUN, OF BRADDOCK, PENNSYLVANIA.

ELECTRIC SWITCH.

SPECIFICATION forming part of Letters Patent No. 621,263, dated March 14, 1899.

Application filed March 28, 1898. Serial No. 675,407. (No model.)

To all whom it may concern:

Be it known that I, ANDREW E. MACCOUN, of Braddock, in the county of Allegheny and State of Pennsylvania, have invented a new and useful Improvement in Electric Switches, of which the following is a full, clear, and exact description, reference being had to the accompanying drawings, forming part of this specification, in which—

10 Figure 1 is a vertical transverse section of my improved switch; and Fig. 2 is a front elevation of the same, partly broken away.

15 My invention relates to the switches or cut-outs employed for breaking heavy electric currents automatically, and especially to those used for large electric elevators and blast-furnace hoists, and it is designed to provide a switch for this purpose which will avoid the liability to heavy sparking or arcing and the 20 consequent destruction of the switch.

25 In the drawings, 2 represents a base-plate having vertical end standards 3 3, within which is carried the shaft 4. This shaft is provided between the standards with a bushing or collar 5, of insulating material, keyed to the shaft, as shown. Surrounding this bushing are a series of disks or plates 6, of conducting material, which are cut away to 30 form radial arms, at the ends of which are secured contact plates or tips 7, which are preferably curved, as shown, and secured to the ends of the arms by countersunk screws. Between the conducting-tips these sections or plates are provided with a layer 8, of an insulating material, and the plates are spaced 35 apart and separated by disks 9, which are preferably of greater diameter than the plates. These plates may be keyed to the insulating bushing or otherwise secured thereto, so as to 40 rotate with the shaft. At each side of the drum thus made up are placed two longitudinal bars 10 10, of conducting material, these bars preferably being reduced at their ends and passing through insulated bushings in 45 the standards, to which they are secured. Each bar is provided with several pairs of spring arms or fingers 11 11, which may be adjusted by set-screws 12, passing therethrough and bearing upon brackets 13, secured to the inner faces of the bars. These 50 spring-arms are adjusted so that they will bear with the desired pressure upon the con-

tact-tips of the sections, each bar having a pair of these arms for each section of the drum. The current is led to one of the longitudinal bars 10 by any suitable connection, such as shown at 14, and when the drum is swung into the position shown in dotted lines in Fig. 1 the spring-arms will bear upon the radial arms of the sections and the current 55 passing through these sections will be taken off by the spring-arms of the opposite bar, from which bar it is led to the desired point. The drum may be oscillated by any suitable connection with the projecting end of the 60 shaft.

The advantages of my invention will be apparent to those skilled in the art, since the current passing through the conducting-bar will be split up and pass in opposite direction 70 through the several fingers and then be collected by the several fingers of the other bar, so that when the drum is swung to the position shown in full lines there will be little or no danger of sparking and burning of the 75 switch.

The device is especially adapted in connection with large electric elevators and blast-furnace hoists and is operated as follows: When the switch is thrown into the position 80 shown in dotted lines, the circuit to the motor is completed, and the operator can throw in his controller and start the hoist. When the hoist reaches the desired height, a screw or cam arrangement geared to the main elevator-drum strikes a lug and shifts the switch into the position shown in full lines independently of the operator or whether his controller is on or off. This breaks the circuit, and the hoist stops at the desired point. To 85 start again, the operator must turn off his controller and again throw the switch into the position represented by dotted lines.

This switch can also be used for short-circuiting the fields of a motor and may be thrown 90 from one position to another by a cam geared to the hoisting-drum, the elevator thus being speeded up and slowed down whenever desired.

Many variations in the form and arrangement of the parts may be made without departing from my invention, since

What I claim is—

1. An electric switch comprising a rotatory

- drum having a series of conducting-sections laterally insulated from each other, a bar to which the current is led, said bar having electrically-connected conducting-fingers arranged to bear upon the sections and split up the current, and another bar having electrically-connected fingers arranged to bear upon the sections and collect the split-up current; substantially as described.
- 10 2. In an electric switch, a shaft or drum having conducting-sections mounted thereon and insulated from each other, each section having projecting conducting-posts, a bar to which the current is led, said bar having a series of electrically-connected spring-fingers arranged to contact with certain of the conducting-posts and split up the current, and another bar having a set of electrically-connected spring-fingers arranged to contact with other of the conducting-posts and collect the current therefrom; substantially as described.
- 15 3. In an electric switch, a bar to which the current is led, having electrically-connected spring-fingers, a movable section having in-

sulated conducting portions arranged to receive the split-up current from the fingers, and another bar having electrically-connected fingers also arranged to contact with the conducting portions of the movable sections and collect the current therefrom; substantially as described.

4. In an electric switch, a shaft or drum having conducting-sections mounted thereon and insulated from each other, each section having a series of projecting conducting-posts, a bar to which the current is led, said bar having at least two series of fingers arranged to contact with certain of the conducting-posts and split up the current, and another bar having at least two sets of fingers arranged to contact with other of the conducting-posts and collect the current; substantially as described.

In testimony whereof I have hereunto set my hand.

ANDREW E. MACCOUN.
